UNITED STATES PATENT OFFICE

132,471

DESIGN FOR A TRUCK TYPE CONCRETE MIXER

Harry C. Peters, Shorewood, Wis.

Application March 10, 1941, Serial No. 99,431

Term of patent 14 years

To all whom it may concern:

Be it known that I, Harry C. Peters, a citizen of the United States, residing at Shorewood, in the county of Milwaukee and State of Wisconsin, have invented a new, original, and ornamental Design for Truck Type Concrete Mixer, of which the following is a specification, reference being had to the accompanying drawings, forming part thereof.

This application is a continuation in part of application Serial No. D-92,021, filed April 29, 1940.

Figure 1 is a perspective view showing the front and one side of a truck type concrete mixer embodying my new design;

Figure 2 is a side elevational view thereof; and
Figure 3 is a perspective view showing the opposite side thereof.

The characteristic features of my design are shown in full lines in the drawings.

I claim:

The ornamental design for a truck type concrete mixer, as shown and described.

HARRY C. PETERS.
